CLAIM

The ornamental design for an arrow vane, as shown and described.

DESCRIPTION

FIG. 1 is a 4X scale front view of the arrow vane;
FIG. 2 is a perspective view illustrating the arrow vane;
FIG. 3 is first side perspective view of the arrow vane;
FIG. 4 is a second side of the arrow vane;
FIG. 5 is a front side elevation of the arrow vane;
FIG. 6 is a rear side elevation of the arrow vane;
FIG. 7 is a 4X scale rear view of the arrow vain;
FIG. 8 is a 4X scale view of the rear side of the arrow vane;
FIG. 9 is a front elevation view of the arrow vane;
FIG. 10 is a rear elevation view of the arrow vane;
FIG. 11 is a 4X scale view of the second side of the arrow vane;
FIG. 12 is a 4X scale view of the first side of the arrow vane; and,
FIG. 13 is a 4X scale view of the front side of the arrow vane.
An ornamental arrow vane is claimed and illustrated. The broken lines in the various drawings are used to illustrate environmental, orientation and overall purpose of the claimed invention and are not to be considered as necessary elements of the claim.
